UNITED STATES PATENT OFFICE.

JOSEPH A. BRYAN AND JAMES BENNETTE FIELDING, OF PRESCOTT, ARK.

STOCK-CAR.

SPECIFICATION forming part of Letters Patent No. 328,916, dated October 27, 1885.

Application filed July 11, 1885. Serial No. 171,346. (No model.)

To all whom it may concern:

Be it known that we, JOSEPH A. BRYAN and JAMES B. FIELDING, citizens of the United States, residing at Prescott, in the county of 5 Nevada and State of Arkansas, have invented certain new and useful Improvements in Cattle Cars; and we do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 Our invention has relation to cattle-cars; and it consists of a new and improved arrangement for feeding cattle while in transit.

In the accompanying drawings, Figure 1 is a side view of the inside of the car with our 20 invention attached. Fig. 2 is a horizontal sectional view of the roof. Fig. 3 is an end view of the roof. Fig. 4 is a detail view of one of the troughs. Fig. 5 is a perspective view of one of the troughs. Fig. 6 is an end 25 view of one of the troughs.

Our invention is described as follows:

The entire top of the car is made so as to form a water-tank, 1, and is so constructed as to be removed at pleasure, and has an 30 opening, 2, at the top to admit the water, and one or more openings, 3, on the side, to which a hose may be attached to convey the water to any part of the car. It also has a horizontal flange on its front end, which fits under the front cross-beam of the car, and perpendicular flanges on the sides and rear end, which fit between the top, side, and rear beams of the car and hold the tank in position.

40 Our troughs 4 are made in five pieces, and hinged together and secured by clasps 5, as shown in Figs. 1, 4, and 5. The bottom *a* has its edges *a' a'* beveled. The leaves or sides *b b'* have their lower edges, *b' b'*, also beveled, so 45 that when the two beveled edges come together the sides stand perpendicular to the bottom. The sides *b* and *b'* are hinged to the bottom *a* by hinges *c*, which are secured on the outer face of the sides and bottom and allow 50 the trough to open out flat. The ends *d*

are hinged on their inner face to the inner face of one of the sides, *b*, by a hinge, *d'*, which allows the end to fold in close to the said side. A clasp, 5, is hinged to the upper edge of one of the sides, and bent at its loose end 55 to clasp the other side of the trough when the same is closed. These troughs are arranged on the inside of the car, as may be seen in Fig. 1, and are held in position by means of guides 12, to which the top leaf of the trough 60 is held by means of an eye, 6, secured in the back part of the same. These troughs are raised or lowered by means of cord 13, winding-shaft 14, beveled gearing 15, ratchet-wheel, foot-dog, and hand-wheel 16, the operation of which needs no description. These troughs may also be attached to the outside of the car, in which case they are held in position by means of guards, and are drawn up and let down by means of cords, winding-shaft, 70 ratchet-wheel, dog, and spring.

We do not in this application claim the mechanism for attaching these troughs to the outside of the car, nor the mechanism for winding up and down, as the same is claimed in our 75 application filed June 15, 1885, Serial No. 168,708, stock-cars.

Having described our invention, what we claim as new, and desire to secure by Letters Patent, is

In combination with a cattle-car for watering and feeding stock, the combination of the troughs 4, having the bottom *a*, the leaves or sides *b b'*, ends *d*, and clasps 5, eyes 6, secured in either end, one near the upper edge and 85 the other near the lower edge on the back of the top leaf, *b*, guides 12, secured perpendicularly in said car and running through said eyes, cords 13, their lower ends attached to the upper edge of said top leaf, *b*, and their upper 90 ends to the winding-shaft 14, which is operated by the beveled gearing 15 and hand-wheel 16, substantially as shown and described.

In testimony whereof we affix our signatures in presence of two witnesses.

JOSEPH A. BRYAN.

JAMES BENNETTE FIELDING.
